(57) **CLAIM**

The ornamental design for a plumbing control, as shown and described.

DESCRIPTION

In a preferred embodiment, the nature of this product is as a plumbing fitting in the form of a shower and/or bath control.

FIG. 1 is a left, bottom, front perspective view of a plumbing control according to my new design;

FIG. 2 is a front elevational view thereof;

FIG. 3 is a left side elevational view thereof, the right side elevational view thereof being a mirror image of the left side shown;

FIG. 4 is a top plan view thereof;

FIG. 5 is a bottom plan view thereof;

FIG. 6 is a rear elevational view thereof;

FIG. 7 is a left, bottom, front perspective view of a plumbing control identical to the first but shown in a different environment;

FIG. 8 is a front elevational view thereof;

FIG. 9 is a left side elevational view thereof, the right side elevational view thereof being a mirror image of the left side shown;

FIG. 10 is a top plan view thereof;

FIG. 11 is a bottom plan view thereof; and,

FIG. 12 is a rear elevational view thereof.

The broken line representations of handle environment in the figures and of back side structure in FIGS. 6 and 12 are for the purpose of illustration only, and form no part of the claimed design.
